Des. 233,946
Patented Dec. 17, 1974

233,946

COMBINED FLIGHT PLAN SEQUENCE REMINDER AND MILEAGE SCALE

James L. Wallace, Weatherford, Tex.
(501 Coal Bank Road, Doylestown, Ohio 44230)

Filed Apr. 26, 1973, Ser. No. 354,863

Term of patent 14 years

Int. Cl. D10—04

U.S. Cl. D52—6 A

FIG. 1

FIG. 3

FIG. 4

FIG. 2

FIG. 1 is a rear elevational view of a combined flight plan sequence reminder and mileage scale showing my new design;

FIG. 2 is a bottom plan view;

FIG. 3 is a right side elevational view; and

FIG. 4 is a front elevational view.

I claim:

The ornamental design for a combined flight plan sequence reminder and mileage scale, as shown and described.
